UNITED STATES PATENT OFFICE.

ISAIAH B. LIBBEY, OF CHARLOTTESVILLE, VIRGINIA.

COFFER-DAM.

1,057,859.

Specification of Letters Patent. Patented Apr. 1, 1913.

Application filed June 25, 1912. Serial No. 705,812.

To all whom it may concern:

Be it known that I, ISAIAH B. LIBBEY, a citizen of the United States, residing at Charlottesville, in the county of Albemarle and State of Virginia, have invented new and useful Improvements in Cofferdams, of which the following is a specification.

The invention has for its object to supply a structure of the nature specified which may be placed in position with despatch and which may be removed after the work has been performed, said removal being facilitated by the particular construction which admits of the lock joints being released from the interior preliminary to abandoning the interior prior to separating the sections when taking the device apart.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a side view of a cofferdam embodying the invention. Fig. 2 is a vertical section thereof on the line 2—2 of Fig. 3. Fig. 3 is a horizontal section on the line 3—3 of Fig. 1. Fig. 4 is a detail perspective view of one of the plates or sections prior to being curved. Fig. 5 is a detail perspective view of the edge portions of adjacent plates or sections, showing the locking strips, the plates being separated and flat. Fig. 6 is a horizontal section on the line 6—6 of Fig. 5.

Corresponding and like parts are referred to in the following description, and indicated in all the views of the drawings, by the same reference characters.

The structure embodies a plurality of piles 1, which are set in position at the place where the pier or other structure is to be erected. A skeleton framework is placed in position about the piles 1 and comprises a series of rings 2, which are placed one above the other and held in position by tie rods 3. The rings 2 are of angle formation in cross section, one of the wings or flanges having a vertical arrangement and the other being disposed horizontally. The vertical

wings or flanges support the inclosing plate or sections 4, whereas the horizontal wings or flanges receive tie rods. After the piles have been placed in position a ring is arranged to encircle the upper ends of the piles and the lower ends of the first set of tie rods are fastened thereto, after which the ring is lowered and a second ring placed in position and secured to the upper ends of the tie rods. The tie rods have end portions threaded for a short distance and receive a pair of nuts between which the horizontal wings or flanges of the rings are clamped. After the second ring has been secured to the ends of the first set of tie rods a second set of tie rods is secured to the second ring, after which the structure is lowered and a third ring placed in position and secured to the upper ends of the second set of tie rods when a third set of tie rods are secured to the third ring. The skeleton structure is similarly formed until of the required length, the structure being lowered step by step as each ring is placed in position and made secure. For lowering the structure a tackle is provided and fitted to the upper ends of selected piles, as indicated in Fig. 1. After the skeleton structure has been constructed and lowered into place the inclosing sections or plates 4 are placed in position about said structure. The plates or sections 4 constitute elements of the shell or inclosing walls of the cofferdam and are braced and strengthened by the skeleton structure, the latter sustaining the external pressure of the water after the cofferdam has been pumped out. The sections 4 consist of metal plates of suitable width and of a length corresponding to the height of the cofferdam so that their lower ends may penetrate the bed of the water and their upper portion project above the level of the water at high tide. Strips 6 are placed upon opposite sides of a vertical edge portion of each plate or section 4 and are secured thereto by rivets or fastenings 7. The strips 6 project a short distance from the vertical edge of the plate or section so as to form a space 7 which receives the vertical edge portions of the adjacent section or plate 4. In this manner a mating joint is formed between the abut-

ting edge portions of adjacent plates or sections.

Locking strips 8 and 9 are secured to vertical edge portions of each plate or section 4 and their outer edges are recurved, as indicated at 10 and 11 so as to interlock and retain the sections in place. The lock strips 8 and 9 are secured at their inner edges to the plates 4 and curve outwardly from said plates toward their outer edges so as to form spaces opposite the joints between the plates or sections 4 when said sections are placed together and the outer recurved edges of the locking strips are in engagement. These spaces are indicated most clearly in Fig. 3 and are adapted to receive a cement or concrete 12, whereby the joints between the sections or plates 4 are made tight so as to exclude the passage of water.

The locking strips are secured to the outer sides of the plates 4 and are attached thereto in a manner to admit of their ready removal and for this purpose bolts 13 are employed as the fastening means, the heads of the bolts facing inward. The locking strips have threaded openings to receive the threaded ends of the bolts or fastenings 13, as indicated most clearly in Fig. 6. The sections are prevented from inward movement by reason of their edges abutting and outward movement is prevented by the interlocking of the recurved edge portions 10 and 11 with the locking plates. Lateral displacement of the abutting ends of the plates or sections 4 is prevented by the strips 6, which embrace opposite sides of the edge portions of adjacent plates. The plates or sections 4 are slipped into position from above with the vertical edge of one plate passing into the space 7 of the plate already in position and with the recurved edge portions of the locking strips in engagement, the plate lowering being assisted in its descent by a driver such as employed for driving the piles into the bed of the body of water. After the cofferdam has been set up cement or concrete is forced into the spaces 12 to render the joints tight and after the cement has set the water is pumped from the cofferdam in the usual manner to admit of the work being performed. After the pier has been constructed or the required work performed the fastenings securing the locking strips to the shell of the cofferdam are loosened and the locking strips 8 and 9 removed, thereby admitting of the sections or plates 4 being easily removed. The skeleton structure is elevated step-by-step, each of the rings being removed in succession together with the tie rods in the reverse order practised in assembling said parts.

From the foregoing description, taken in connection with the accompanying drawings, the advantages of the construction and

of the method of operation will be readily apparent to those skilled in the art to which the invention appertains, and while I have described the principle of operation of the invention, together with the device which I now consider to be the embodiment thereof, I desire to have it understood that the device shown is merely illustrative, and that such changes may be made when desired as are within the scope of the claims appended hereto.

Having thus described the invention what is claimed as new, is:—

1. A cofferdam comprising an outer shell and an inner supporting structure of skeleton form and comprising rings and sets of tie rods.

2. A cofferdam comprising an outer shell and an inner supporting structure of skeleton form and comprising rings and sets of tie rods, each of said rings consisting of a vertical flange and a horizontal flange, the latter having openings and the tie rods being arranged to pass through the openings in the horizontal flanges of the rings and serving to connect the same in series.

3. In a cofferdam and in combination with an inclosing shell, a supporting structure of skeleton form arranged within the shell and comprising superposed rings and tie rods, each of the rings comprising a vertical flange and a horizontal flange, the latter having openings to receive the tie rods, the latter having their end portions threaded and receiving pairs of nuts, a set of tie rods being provided for each two rings.

4. In a cofferdam, a shell formed of vertically arranged plates having their edge portions abutting, and locking strips secured to the plates near their vertical edges and having their outer edge portions oppositely recurved to interlock.

5. In a cofferdam, a shell formed of vertically arranged plates having their edge portions abutting, and locking strips secured to the plates near their vertical edges and having their outer edge portions oppositely recurved to interlock, said locking strips inclosing spaces opposite the joints between the plates to receive a material for rendering the joints between the plates water tight.

6. In a cofferdam an inclosing shell formed of a plurality of vertically arranged plates having their edge portions abutting, locking strips having their outer edge portions recurved to interlock and spaced from the plates to inclose spaces, said locking strips having their opposite edge portions placed against the plates, and means for detachably connecting the locking strips to the plates.

7. A cofferdam comprising a shell formed of vertically arranged plates having their

edges abutting, strips embracing opposite sides of the plates at the joints and secured along their edges to one of the plates, locking strips placed against the outer sides of the plates and having adjacent edge portions recurved and interlocked and spaced from the plates, the opposite edge portions of the locking strips touching the plates, and fas-

tenings detachably connecting the locking strips to the plates. ¹⁰
In testimony whereof I affix my signature in presence of two witnesses.
